US00D889209S

(12) **United States Design Patent** (10) **Patent No.:** **US D889,209 S**
(45) **Date of Patent:** **** Jul. 7, 2020**

(54) **CONTAINER ENCLOSURE**

(71) Applicant: **CAMCAL ENTERPRISES, LLC**,
Phoenix, AZ (US)

DE 4126215 A1 2/1993
DE 102004025620 A1 2/2006

(Continued)

(72) Inventors: **Matthew T. Campbell**, Cave Creek,
AZ (US); **Adam Callinan**, Manhattan
Beach, CA (US)

(73) Assignee: **Camcal Enterprises, LLC**, Phoenix,
AZ (US)

(**) Term: **15 Years**

(21) Appl. No.: **29/714,002**

(22) Filed: **Nov. 20, 2019**

FOREIGN PATENT DOCUMENTS

(63) Continuation of application No. 29/688,748, filed on
Apr. 24, 2019, now Pat. No. Des. 869,909, which is
(Continued)

DE 4126215 A1 2/1993
DE 102004025620 A1 2/2006

(Continued)

(51) **LOC (12) Cl.** **07-01**

(52) **U.S. Cl.** **D7/608**
USPC **D7/608**

U.S. PATENT DOCUMENTS

441,228 A 11/1890 Cherbonnier
460,918 A 10/1891 Kraetzer

(Continued)

FIG. 1 is an isometric view of a front, top, and right side of
an ornamental design for a container enclosure;

FIG. 2 is a front elevational view of the container enclosure
of FIG. 1;

FIG. 3 is a rear elevational view of the container enclosure
of FIG. 1;

FIG. 4 is a right side elevational view of the container
enclosure of FIG. 1;

FIG. 5 is a left side elevational view of the container
enclosure of FIG. 1;

FIG. 6 is a top plan view of the container enclosure of FIG.
1; and,

FIG. 7 is a bottom plan view of the container enclosure of
FIG. 1.

The dash-dash-dash lines are for the purpose of illustrating
environmental structure and form no part of the claimed
design. The dash-dot-dash line forms no part of the claimed
design and represents a boundary line.

1 Claim, 4 Drawing Sheets

Related U.S. Application Data

a continuation of application No. 29/670,065, filed on Nov. 13, 2018, now Pat. No. Des. 852,001.
